GAME

Filed Oct. 5, 1922

UNITED STATES PATENT OFFICE.

ROBERT DONER, OF CHICAGO, ILLINOIS.

GAME.

Application filed October 5, 1922. Serial No. 592,650.

To all whom it may concern:

Be it known that I, ROBERT DONER, a citizen of the United States, and a resident of Chicago, in the county of Cook and State of Illinois, have invented a new and useful Improvement in Games, of which the following is a full, clear, and exact description.

My invention relates to a game, more particularly that type of game in which certain moving parts are manipulated in a manner to ascertain the score of the players.

An object of my invention is to provide a device of the type described having a dial and an indicator hand both of which are movable relative to one another and to their supporting means.

A further object of my invention is to provide a device of the type described in which moving parts may be brought to a stop practically instantaneously, even though they are moving at a relatively high rate of speed.

Another object of my invention is to provide a device of the type described in which the score may not be predetermined by an unfair manipulation of the device.

A further object of my invention is to provide a device of the type described which may be operated upon a base or which may be held in the hand and operated by each player at will.

Other objects and advantages will appear in the following specification, and the novel features of the invention will be particularly pointed out in the appended claims.

My invention is illustrated in the accompanying drawings forming part of this application in which—

Figure 1 is a side elevation of an embodiment of my invention,

Figure 2 is a sectional view of a portion of the mechanism illustrated in Figure 1,

Figure 3 is a front elevation of the dial and indicator hand,

Figure 4 is a sectional view along the line 4—4 of Fig. 1, and

Figure 5 is a sectional view along the line 5—5 of Figure 1.

In carrying out my invention, I make use of a base 1 and an upright supporting mem-

ber 2. This base and supporting member is employed for supporting the movable parts of my device when the device is used upon a table or other suitable supporting device.

The movable parts of my device consist in a body member 3 having an opening 4 transversely disposed therethrough for receiving a bolt 5 projected through the supporting member 2, whereby the body member 3 may be pivotally supported upon the member 2 as shown in Figure 1. The body member 3 is provided with a hand grip portion 6 which gives the body member the general appearance of the hilt of a sword. It is obvious that if the body member is removed from the member 2 that it may be gripped in precisely the manner as the hilt of a sword. This manner of holding the device is especially well adapted for use when it is not desired to use the game on a table or the like. A relatively long sleeve 7 is rotatably mounted in the body member 3 and extends outwardly at either end thereof. A shaft 8 is rotatably mounted within the sleeve 7 and its ends project beyond the outer ends of the sleeve 7. A pair of tubular members 9 and 10 are loosely disposed concentric the sleeve 7 on either side of the body member 3. These members 9 and 10 each are disposed with their ends short of the outer ends of the sleeve 7.

The sleeve 7 is provided at what I choose to call the rear end of the device with a hand wheel 11 having much the shape of a six pointed star, (see Figure 5,) and at its forward end with an indicating member 12. The hand wheel member and the indicating member 12 are each secured upon the sleeve 7 by means of set screws 13. The indicating member 12, (see Figure 4,) consists in a metal member having the shape of an arrow and having its mass disposed so that each end of the arrow is of the same weight. One end of the indicator 12, that end resembling the head of an arrow 14, is provided with an opening 15 therethrough and a shaft 16 diametrically disposed in the opening. A steel ball 17 is rotatably mounted upon the shaft 16. The head portion 14 is provided with a point 18 that is bent back

- upon the main portion of the head in the manner shown in Figure 2. The point 18 is therefore in a plane slightly away from the plane of the main portion of the arrow.
- 5 The shaft 8 is provided at its rearward end with a dial 20, (see Figure 3). The dial is divided into a plurality of equal sectors 21 and each sector is given a certain value that is indicated by the printed legends 22 thereupon. The dial 20 is further provided with an opening 23 adjacent the periphery thereof in registration with each of the sectors 21. In the particular dial shown in Figure 3 there are 36 sectors and the numerals or legends assigned to the sectors range from 1 to 12 inclusive. It should be understood at this time that various other divisions of the dial 20 could be made and the legends varied to suit the particular requirements or rules of the game.
- 10 Further inspection of Figure 3 will show that the steel ball 17 will travel in a circular path as the indicator arrow 12 is rotated with the shaft 8 and that this path will be 15 in exact registration with the openings 23 in the dial plate 20. In the present device I choose to construct the dial plate 20 of hard steel so that constant contact with the steel ball 17 will not mutilate the plate.
- 20 From the foregoing description of the various parts of the device, the operation thereof may be readily understood. Ordinarily I prefer to use my device upon the supporting base as shown in Figure 1. In operation 25 the device is first moved to the position shown in full lines in Figure 1, or perhaps more preferably the way of operating the device would be to tilt the forward end downwardly to insure the disengagement of 30 the dial 20 with the steel ball 17. However, under ordinary circumstances the main portion of the device may rest in a horizontal plane. The player first grasps the hand wheel 9 and with a swift movement of the 35 hand rotates this wheel, which in turn will cause the shaft 8 to turn and the relatively heavy dial plate 20. The dial 20 because of its own mass will possess considerable momentum and therefore continue in its rapid 40 rotation for some time. The next movement of the player is to move the star shaped hand wheel 11 so that the sleeve 7 turns. This will cause the indicating hand 45 12 to rotate about the rapidly rotating shaft 8 and the indicator hand 12 will move relative to the plate 20 as well as the base member 1. The player then grasps the portion 50 6 and moves the device to the position shown in dotted lines in Figure 1. This 55 movement will cause the relatively heavy plate 20 of its own weight to move into forceful contact with the slidably outwardly projecting ball 17 and the ball 17 will engage one of the openings 23 which movement will bring the dial plate 20 to a sudden 60 stop. The legend opposite that opening 23 in which the ball finally rests, (see Figure 3), will indicate the value of the score head.
- 65 If the player does not desire to use the base 1, he merely grasps the body member 3 70 in the hand as he would grasp the hilt of a sword and operate the moving parts of the device in precisely the same manner as though the device were mounted upon the support 2 of the base 1.
- 75 An important advantage of my present invention is that when the device is tipped downwardly, as shown in dotted lines in Figure 1, and the dial 20 rotated in the manner described, the player is unable to 80 observe the legends upon the dial and therefore is unable to ascertain by observation just when to tilt the device to cause the indicator to register with a predetermined legend. It should be noted that the device 85 is so balanced that the dial normally rests downwardly, the handle portion being elevated for ready access thereto. A resilient stop 25 is provided and is shown at the base 90 of the upright member 2 by means of which the handle 19 may be limited in its downward movement as the dial is elevated.
- 95 I claim:
1. A device of the character described comprising a movable dial, a movable indicator hand for said dial, means for manually moving said dial and said hand independent of one another and means for moving said dial into engagement with said hand, whereby the dial and the hand become set against movement relative to one another and both may come to a quick standstill.
- 100 2. A device of the character described comprising a base, a body member pivotally supported on said base, a dial rotatably mounted on said body member, said dial having a plurality of legends on its outer face adjacent the periphery thereof, and openings through said dial adjacent each of said legends, an indicator hand for said dial rotatably mounted on said body member, a ball rotatably supported on said indicator hand and in registration with the openings in said dial when said dial is rotated, and means for manually rotating said dial and said indicator hand independent of one another, said dial being arranged so that the openings therein may engage said steel ball on said indicator hand when said body member is tilted relative to said base and said ball will finally rest in one of the openings in said dial.
- 105 3. A device of the character described comprising a body member, a dial rotatably and slidably mounted on said body member, said dial having a plurality of legends thereon having given values, and openings through said dial, one for each of said legends, the openings being arranged in an 110
- 115 120
- 125 130

nular alignment adjacent the periphery of the dial, an indicator hand for said dial rotatably mounted on said body member, a metal ball rotatably mounted on said indicator hand and arranged to register with the openings in said dial as said dial is rotated, and means for manually rotating said

dial and said indicator hand independent of one another, said dial being arranged so that it will slide into engagement with the ball 10 in said indicator hand when the body member is tilted manually.

ROBERT DONER.
